LUDWIG DÜRR, OF FRIEDRICHSHAFEN, GERMANY, ASSIGNOR TO LUFTSCHIFFBAU ZEPPELIN GESELLSCHAFT MIT BESCHRANKTER HAFTUNG, OF FRIEDRICHSHAFEN, BODENSEE, GERMANY

LIGHT-WEIGHT GIRDER

Application filed February 6, 1928, Serial No. 252,231, and in Germany February 15, 1927.

My invention relates to light weight girders or trusses and more especially to metal elements of this kind that are designed to be used in aircraft construction.

Generally these truss girders include channels or other structural elements serving as upper and lower chords which are connected by lattices forming the truss bracing or webs. It has become usual in airship construction for example to arrange these lattices always in cross-wise relation and in pairs. The crossed lattices are inserted in sequence between the members forming the truss chords and the distance from the end of one lattice 10 cross to the beginning of the next lattice cross is less than the distance between the shanks of a lattice cross itself measured on the chords. This means that the lattices are secured to the chords at irregular or un-even distances. Therefore when the truss is under load the chords will give way sidewise at those points where the above mentioned distances are greater.

According to this invention the disadvantage mentioned is obviated by arranging the ends of the lattices at shorter distances which are approximately equal each other, so that there are no more individual lattice crosses but every lattice of one side running in one direction crosses at least two of the lattices on the other side running in the other direction. Consequently, every lattice, besides having its ends fixed to the chords, is secured at least at two points along its length to the crossing lattices of the other side, by means of screws or rivets. Of course, in cases in which the distance between the chords is sufficient every lattice may cross and be riveted to three or more lattices of the other side running in the other direction. However, the principal feature is that the chords are held by the lattices at substantially regular and equal distances. This primary object of my invention may, for example, also be attained by branching the ends of the lattices in such manner that the branches fastened to the chords hold them in regular or equal distances. But this manner of constructing the girders does not produce the same strength in the web between the chords as the first mentioned manner.

Having given a general description of my invention I now want to point it out more in detail referring to the drawings which represent examples embodying my invention.

Figures 1, 2 and 3 are elevational views of 55 girder portions.

The upper and the lower chords, both are designated by the letter *a*. They are braced by lattices *b*, *b*₁ and *b*₂.

In Fig. 1 which illustrates one form of 60 construction embodying the invention the lattices *b* are riveted to the chords from one side, whereas the lattices *b*₁ are fastened to them from their other side. The distance *d* of the fastening points of the lattices on the chords are substantially equal to each other, so that the channels or members forming the chords are held in regular or equal distances. The lattices *b* and *b*₁ are connected to each other at 65 their crossing points *c*.

In Fig. 2 the lattices *b* and *b*₁ are so arranged as to cross each other at three places instead of two. Accordingly, each lattice is fastened to three other lattices. On the 70 chords the distances *d* between the fastening points of the lattices again are substantially 75 equal.

At the right hand side of this figure, a portion of the girder is shown in which every other middle portion of the lattices where they have their middle crossing is cut out. Thus there are lattice crosses, each of the four ends of which has an additional branch, one end thereof being riveted to the lattice leg, 80 and the other end to the corresponding chord. In certain cases this lighter construction may suffice for holding the chords in regular 85 distances.

In the example represented in Fig. 3 the 90 same principle is applied, only the additional branches are not constructed as individual parts but integral with the main lattices *b* and *b*₁. This construction is applicable with 95 regard to trusses wherein relatively less lattice strength or rigidity is required and it has the advantage of saving some of the riveting work.

I do not want to be limited to the details 100 described or shown in the drawings as many

variations will occur to those skilled in the art.

• What I claim is:

- A light weight truss girder for aircraft comprising an upper chord, a lower chord, a series of substantially parallel lattices extending between said chords obliquely thereto, means for fastening such lattices to corresponding sides of the chords, a second series 10 of parallel lattices obliquely arranged with respect to the chords transversely of the first series of lattices, the second series being fastened to the chords and to the first series of lattices, relatively short struts having one end of each connected between the ends of a plurality of the lattices and having their other ends connected to the chords, said struts extending transversely with respect to adjacent lattices and terminating at 15 the location of their intersection therewith, and means for fastening the struts to the lattices.
